UNITED STATES PATENT OFFICE.

RICHARD U. BAILEY, OF SPRINGFIELD TOWNSHIP, SUMMIT COUNTY, OHIO.

TOY CAR.

1,333,370.

Specification of Letters Patent.

Patented Mar. 9, 1920.

Application filed April 28, 1919. Serial No. 293,301.

To all whom it may concern:

Be it known that I, RICHARD U. BAILEY, a citizen of the United States, residing in Springfield Tp., county of Summit, and 5 State of Ohio, have invented new and useful Improvements in Toy Cars, of which the following is a specification, reference being had to the accompanying drawings.

The invention relates to a toy car.

10 The object of the present invention is to improve the construction of toy cars for children, and to provide a simple, practical and inexpensive child's car of strong and durable construction designed for use similar to an ordinary "kiddy car" and equipped with means for causing the car when propelled to rock from side to side thereby affording increased amusement and increasing the attractiveness of the toy.

15 With these and other objects in view, the invention consists in the novel construction and arrangement of parts hereinafter fully described, illustrated in the accompanying drawing, and pointed out in the claim 20 hereto appended, it being understood that various changes in the form, proportion and minor details of construction, within the scope of the claim, may be resorted to without sacrificing any of the advantages or departing from the spirit of the invention.

In the drawing:—

Figure 1 is a plan view of a toy car constructed in accordance with this invention.

Fig. 2 is a side elevation of the same.

35 Fig. 3 is a rear elevation of the car. Like numerals of reference designate corresponding parts in the several figures of the drawing.

In the accompanying drawing in which is 40 illustrated the preferred embodiment of the invention, the toy car comprises a frame or body 1 preferably composed of a top horizontal seat board 2 and a rear vertically disposed bolster piece or member 3 which is supported by a centrally arranged front brace 4. The centrally arranged brace 4 is located in advance of the bolster member 3 and is approximately triangular as clearly 45 shown in Fig. 2 of the drawing to fit the under side of the seat board 2 and the bolster member 3 and is secured to the same by screws or other suitable fastening devices. The seat piece 2 which may be of any desired configuration, is preferably reduced at its front portion 5 as illustrated in Fig. 1 of the drawing, and the said front portion 5 is supported by

a vertical pivoted fork 6 having an upper rounded bearing portion 7 which is journaled in a suitable opening 8 in the reduced front portion 5 of the seat board or member 2. The front fork 6 is preferably bifurcated at its lower portion 9 and is provided with suitable bearings for a front shaft or axle 10 on which is centrally mounted a front wheel 11. The front fork is provided at its upper portion with suitable stops 12 located at the upper and lower faces of the reduced front portion of the seat board or member and the said front fork which is also equipped at its upper end with a suitable handle 13 is 65 adapted to rotate in the bearing opening 8 for guiding the toy car. The body wheels, front fork and other parts are preferably constructed of wood with the exception of the fastening devices, the axles and the bearings, but it will be readily understood that any suitable material may be employed in the construction of the toy car, and that the latter may be made in various sizes for the use of children of different ages. 80

The rear bolster member 3 is provided at the lower end with suitable bearings 14 for the reception of a rear axle 15 and the upper end of the bolster member 3 is suitably secured to the rear portion of the seat board 85 or member 2 of the body. The lower end of the bolster member is preferably grooved at 16 to receive the rear axle 15 which projects laterally from the said bolster member 3 and the bearings 14 may consist of any suitable 90 fastening means.

The extended ends of the rear axle 15 are arranged in eccentrically arranged bearing openings 17 of rear wheels 18 and are provided with suitable heads 19 for retaining 95 the rear wheels on the rear axle. The bearing openings of the wheels may be lined or planed as desired and the heads 19 may consist of any suitable fastening means. The bearing openings 17 are arranged a short 100 distance off center preferably one-half inch or less for causing the toy car to rock laterally from side to side as the car is propelled and the degree of rocking movement may be controlled by varying the distance of the eccentric bearing openings 17 from the center 105 of the rear wheels. The rotary movement of the rear wheels and the lateral rocking movement of the toy car will increase the pleasure or amusement derived from the use 110 of the car and the attractiveness of such toy will be materially increased.

What is claimed is:—

A toy car comprising a body; a front wheel pivotally mounted at the front end thereof; means for controlling the pivotal motion of 5 said front wheel; a vertical bolster rigidly mounted at the rear end; axle bearings formed upon the lower end of the bolster; an axle journaled in said bearings; a wheel rigidly and eccentrically mounted on each

extended end of the axle, through points off- 10 center and oppositely positioned as to each wheel, so as to impart a side swing to the vehicle and which side swing is accentuated by the vertical height of the bolster.
